Attorneys

UNITED STATES PATENT OFFICE.

FREDERICK C. OVERBURY, OF HILLSDALE, NEW JERSEY, ASSIGNOR, BY MESNE ASSIGNMENTS, TO THE FLINTKOTE COMPANY, OF BOSTON, MASSACHUSETTS, A CORPORATION OF MASSACHUSETTS.

PROCESS OF PRODUCING ORNAMENTAL ROOFING.

1,398,272.

Specification of Letters Patent. Patented Nov. 29, 1921.

Application filed March 6, 1917. Serial No. 152,492.

To all whom it may concern:

Be it known that I, FREDERICK C. OVERBURY, a citizen of the United States, residing at Hillsdale, in the county of Bergen 5 and State of New Jersey, have invented new and useful Improvements in Processes of Producing Ornamental Roofing, of which the following is a specification.

This invention has relation to prepared 10 roofing elements and more particularly to those which are designed to be separately arranged on the roof in simulation of wooden or mineral shingles or tiles. Usually such elements are in the form of what are termed 15 shingles or shingle strips, and they are more or less flexible, being cut from sheets of prepared weatherproof material. In order that such elements may be used on dwellings and high grade structures, they have heretofore 20 been ornamented, and incidentally rendered more fire-proof, by the application to the surface thereof of crushed mineral such as slate, earthenwear tile, granite and the like, and indeed such crushed minerals of different 25 colors have been so placed on the elongated sheets of roofing material to constitute conventional predetermined designs. Ordinarily, however, the shingles and shingle strips have had the surface thereof 30 coated with crushed mineral of one color or another so that the entire area of such elements, when placed on the roof, presents an unvarying color, shade or tint. While the provision of such shingles or shingle strips 35 have greatly enlarged the scope of their usefulness, nevertheless they have failed to meet the demands of those who are insistent upon certain esthetic and ornamental effects. That is, notwithstanding that mineral coated 40 roofing elements have attained a certain vogue and have been used in large quantities on the roofs of dwellings, yet when laid they present a flat and unvarying and hence 45 uninteresting monotonous appearance which is offensive to those who have artistic tastes.

Natural building materials, such as wooden shingles, when exposed to the weather, even when stained, are so acted upon by the wind and weather, as to present different 50 shades or tints or colors in different unpredictable areas, just as seam-faced granite because of its natural formation presents to the eye beautiful varied color tones.

I have discovered that it is possible to

destroy the monotonous effect produced on 55 the eye by the mineral coated elements when laid on the roof, by employing crushed minerals of different colors and shades, and so applying the same to the elements in the process of manufacture, as to provide variable 60 areas having one color and variable areas of other color with intervening areas where the colors blend or shade from one to the other, these various areas constituting no predetermined or related designs but occurring 65 very much as they occur in seam-faced granite or other natural materials. This result may be accomplished by the employment, for example, of green and red 70 crushed slates, which are delivered to the sheet of adhesive-coated fabric in such way that portions or areas on the sheet are coated only with red slate, other portions or areas with red slate, and the intervening portions or areas with a mixture of the two different-colored 75 materials.

Upon the accompanying drawings, I have illustrated conventionally a form of apparatus which may be employed in manufacturing roofing elements embodying the invention and for practising the invention.

Referring to said drawings,—

Figure 1 represents conventionally instrumentalities embodying one form of my improvements and which may be employed for 85 the manufacture of my improved shingle strips.

Figs. 2 and 3 represent the instrumentality for applying the differently colored crushed mineral materials.

Fig. 4 represents an attempt to illustrate the sheet of material and to show the areas of different colors thereon.

Fig. 5 represents a longitudinal section through a valve by which the crushed mineral is fed to the machine shown in Figs. 2 and 3.

Figs. 6 to 9 inclusive represent transverse sections through the multiple valve.

Fig. 10 represents a cross section showing 100 the valve closed.

Fig. 11 illustrates the end of the valve mechanism.

Figs. 12 to 13 illustrate another form of valve mechanism which may be used.

It will of course be understood that the drawings are more or less diagrammatic and show the several instrumentalities more

or less conventionally, and that the latter may be of any approved construction or design. The instrumentality first in order of operation is an apparatus for saturating 5 or impregnating a sheet of fibrous material such as felt or the like with the usual waterproofing composition of a hydrocarbon or bituminous nature. This is indicated at A, and it may comprise a suitably heated tank 10 or vat 20 for containing said compound, through which the sheet *a* is drawn from a roll *b*. Squeeze rolls 21 remove the surplus compound from the now saturated sheet prior to its passage to the next instrumentality. 15

The second apparatus is indicated at B, and it is an apparatus for applying to one face of the saturated sheet a coating of pitch or asphalt having the desired consistency 20 and melting point at ordinary temperatures. This material is applied in a molten or plastic adhesive condition and extends from edge to edge of the sheet. Between the two instrumentalities A and B may be arranged 25 additional cooling rolls if desired. As shown the apparatus B has the cooling rolls 22, and the rolls 23, 24, in connection with the latter of which there is the receptacle 25 for the molten pitch or asphalt, which is spread on 30 the surface of the impregnated sheet.

The third instrumentality is indicated at C and applies the different mineral materials to the sheet while the bituminous coating thereon is still adhesive. The particular description of this machine is given herein-after.

The fourth instrumentality D is the machine which cuts the sheet into the roofing elements. Any suitable machine may be 40 used for this purpose for either longitudinally slitting the sheet and transversely severing it at intervals to form shingles of oblong or other shapes, or else cutting it into shingle strips such as shown in Letters 45 Patent No. 1,150,298, dated August 17, 1915. For example, the machine shown is similar to that shown and described in my Letters Patent No. 1,182,417, dated May 9, 1916, and includes the feeding rolls 26, the cutting 50 rolls 27, and the chopping knife 28 for forming the sheet *a*, the shingle strip *c* having the spaced tabs or projections *d*. In lieu of the machine thus conventionally illustrated, I may employ any other equivalent machine 55 for producing the detached roofing elements.

Between the third and fourth instrumentalities may be arranged a festooning and cooling mechanism of any suitable sort, although I have not thought it necessary to 60 illustrate the mechanism as it is well known.

Returning now to the surfacing machine C, I have shown it as provided with cooling rolls or cylinders 29, and also with the rolls 30, 31, to the former of which the coated 65 fabric passes from the machine B, while the

coating is still in an adhesive condition. Arranged in operative proximity to the roll 30 is a trough 32 which extends from end to end of the roll and to which the differently colored surfacing minerals are delivered, 70 and from which it is fed to the coated fabric. This trough has the feeding roll 132. This material adheres to the coated sheet and is partially embedded therein as the sheet 75 passes between rolls 30 and 31, the surplus mineral material falling back to the trough as the sheet passes over roll 31 to the cooling rolls or drums 29. The differently colored surfacing minerals are contained in separate compartments or receptacles and are delivered 80 in batches to the trough. They may be manually shoveled into the trough in such way as to secure the desired result, but I have shown conventionally an automatic mechanism for feeding them to the trough, 85

which I shall now describe. A hopper 33 is divided longitudinally by a partition 34 into two compartments 35, 36, of which the former may contain for example red crushed slate, and the other green crushed slate. 90 These compartments converge at their lower ends to a valve casing 37 in which I have shown a multiple valve 38. This valve has four passageways for the mineral material therethrough, two as at 40 and two as at 41, 95 those at 40 and 41 alternating. These are so arranged that, when the valve passages 40 communicate with compartment 36, those at 41 communicate with compartment 35 and vice versa. Thus at the same time two 100 streams of red slate are being delivered to certain portions of the trough and two streams of green slate to other portions thereof. On rocking the valve to its other operative positions, the streams of red slate 105 are cut off and are followed by streams of green slate, and the streams of green slate are cut off and are followed by streams of red slate. Thus there are delivered to the troughs different batches of colored mineral, 110 and there are strata of red in each batch with intervening strata of green. Where these batches meet, the materials mingle or mix as will be well understood, as there is nothing to separate them. Hence, as the 115 coated sheet passes the trough, unconventional patches of green and red slate will be applied respectively to different portions or areas of the sheet, between which areas will be areas in which the two colors 120 will be mixed or blended without any lines of demarcation. Thus the sheet will present a more or less mottled appearance as indicated conventionally in Fig. 4. The valve may be operated by hand, but, if desired, it 125 may be operated automatically. To this end, I may affix to the valve a weighted arm 43 connected by a rod 44 to a lever 45 oscillated by a cam 46. The latter may be driven by a belt 47 and pulleys 48, 49, the latter be-

ing operated by roll 30. The rod 44 is shown as detachably hung on a pivot 50 on weighted arm 43, but, by lifting the latch 51, the rod 44 may be disconnected therefrom, 5 allowing the arm 43 to drop to move the valve in position to cut off both streams of mineral to the trough, as indicated in Fig. 10. When the rod is disconnected, the valve may be operated manually. The valve 10 mechanism, which I have illustrated and described, may be replaced by any mechanical equivalent therefor, which will readily suggest itself. For example, in Figs. 12 to 13 I have illustrated the two large hoppers or 15 receptacles 60, 61, from which lead the spouts 62, 63, for the purpose of delivering the differently colored grit to the hopper 32. These spouts are controlled by sliding valves or gates 64, 65, which may be operated manually or automatically as desired. Other 20 forms of valve mechanism may be employed, or, as previously stated, the different batches of differently colored grit may be shoveled by hand into the hopper 32.

Having thus explained the nature of my 25 said invention in roofing elements and described a process and one set of instrumentalities for producing the same, what I claim is:—

The herein described process of making 30 mineral surfaced ornamental roofing elements, which consists in passing a sheet of adhesive-coated fibrous material under a mass of crushed mineral material, consisting of alternating strata of differently colored 35 material, each stratum consisting of alternating bodies of differently colored material, and causing said differently colored mineral materials to adhere in irregular areas of different colors with intervening areas 40 having a mixture of colors thereon, and then partially embedding said mineral materials by pressure into the adhesive coating of said sheet.

In testimony whereof I have affixed my 45 signature.

FREDERICK C. OVERBURY.
